F. W. BRIGGS.

POCKET CASE.

APPLICATION FILED JAN. 9, 1912.

1,024,674.

Patented Apr. 30, 1912.

UNITED STATES PATENT OFFICE.

FRANCIS W. BRIGGS, OF HENDRUM, MINNESOTA.

POCKET-CASE.

1,024,674.

Specification of Letters Patent. Patented Apr. 30, 1912.

Application filed January 9, 1912. Serial No. 670,292.

To all whom it may concern:

Be it known that I, FRANCIS W. BRIGGS, a citizen of the United States, residing at Hendrum, in the county of Norman and State of Minnesota, have invented a new and useful Pocket-Case, of which the following is a specification.

The device forming the subject-matter of this application is adapted to be employed for carrying about in the pocket, a hypodermic syringe, clinical thermometers, and small vials in which are commonly contained, the tablets which are dissolved in a hypodermic syringe.

15 The present invention aims to provide a device of this type in which an article-holding tray is pivotally connected with a rack, the rack being slidably insertible into a case, the tray being spring-actuated, so as to swing outwardly, through the open front of the rack, thereby permitting a ready removal and insertion of articles into the tray.

20 A further object of the invention is to provide an article-holding tray of novel and improved form, and to provide a rack with which the tray may be pivotally connected.

25 A further object of the invention is so to fashion the device that the articles will be retained securely therein, and be protected both against crushing and against accidental displacement.

30 With the foregoing and other objects in view, which will appear as the description proceeds, the invention resides in the combination and arrangement of parts and in the details of construction hereinafter described and claimed, it being understood that changes in the precise embodiment of invention herein disclosed can be made within 35 the scope of what is claimed without departing from the spirit of the invention.

In the accompanying drawings.—Figure 1 shows the invention in perspective; Fig. 2 shows the invention in front elevation, the 40 rack being partially withdrawn from the case; Fig. 3 is a section upon the line A—B of Fig. 2, the tray being swung backwardly into the rack; Fig. 4 is a section upon the line A—B of Fig. 2, the tray being swung 45 outwardly, through the open front of the rack; Fig. 5 is a transverse section upon the line C—D of Fig. 2; Fig. 6 is a perspective of the tray, parts being broken away; and Fig. 7 is a perspective of an element which 50 is assembled with the rack, to form the bottom of the rack, and to form a spring means

whereby the tray is swung outwardly, away from the rack.

In carrying out the invention there is provided a case 1, relatively thin, compared 60 with its breadth, and open at the top only. The case 1 may be of any size and may be adapted to contain any desired number of bottles. The case 1 is equipped in its front wall with a longitudinal corrugation 2. The 65 case 1 is curved transversely to fit the body when placed in the pocket of a garment.

The invention further includes a rack 3 which is slidably inserted into the case 1. The rack 3 includes a back 4, the edges of 70 which are rolled to form tubular thermometer compartments 5, these tubular elements 5 serving, at the same time, as reinforcements for the rack 3. Outstanding from the back 4 is a top 7 which, when the rack is inserted into the case 1, serves as a closure for the upper end of the case. The compartments are equipped with outstanding projections 8, coöperating with the projections 9 struck from the case 1, as shown at 6, the 80 parts 8 and 9 constituting coöperating elements preventing the complete withdrawal of the rack 3 from the case 1.

The invention further includes a tray 10, pivotally connected adjacent its inner end 85 with the rack 3, so as to swing outwardly, between the tubular compartments 5. The tray 10 includes a back 11, corrugated as shown at 12, to form article-holding seats. The side walls 14 outstand beyond the back 90 11, and the bottom 15 fits between the side walls 14, the bottom being equipped at its outer edge, with a plurality of upstanding resilient, article-holding tongues 16, aligned with the seats 12, the back 11, the sides 14, 95 the bottom 15 and the tongues 16 being, preferably, fashioned in one piece, as will be understood readily from an inspection of Fig. 6. One of the tongues, denoted specifically by the numeral 17, is longer than the other tongues, for a purpose which will be described hereinafter. In the bottom 15, in alignment with the tongue 17, there is an opening 18. In the side walls 14 there are openings 19, adapted to receive pins 20 10 which project toward the longitudinal center of the rack, the pins 20 being secured to the compartments 5. The pins 20, as will be understood readily, serve to effect a pivotal connection between the tray 10 and the rack 11 3, so that the tray 10 may be swung outwardly, away from the rack 3, as shown to

best advantage in Fig. 4. Outstanding from the back 11 of the tray 10 are a plurality of pins 21.

The bottles 22 are engaged by the tongues 16 and fit in the corrugations 12, between the pins 21. In order to prevent a displacement of the corks, ledges 23 outstand from the back 4 of the rack 3. The ledges 23 may be variously placed on the back 4, depending upon the lengths of the bottles 22. The ledges 23 are spaced apart, so that the hypodermic syringe 24 may fit between them the syringe being engaged by the tongue 17, and the point of the syringe passing through the opening 18 in the bottom 15, as will be understood most readily from an inspection of Fig. 3. Plates 100 outstand from the back 11 serve to direct the syringe into the opening 18. Pins 101 projecting from the back 11 and from the tongue 17 engage the lower end of the body of the syringe 24 and prevent an undue descent thereof.

The thermometers 125 are contained within the compartments 5, the top 7 of the rack 3 being provided with screw caps 26, constituting closures for the compartments 5, the construction being such that the thermometers 125 may be removed from the compartments 5, if desired, without withdrawing the rack 3 from the case 1. Obviously, as is a common and well known construction, the caps 26 may be secured to the ends of the thermometers 125.

In order to maintain the rack 3 within the case 1, a lock is provided, the same including a button 27, rotatable in the top 7 of the rack 3, the button being equipped at its inner end with an outstanding, eccentric head 25, adapted to lock beneath a projection 29 in the front wall of the case 1, the projection 29 preferably being formed by extending the wall of the case outwardly to a slight extent. The button 27 projects beyond the case 1 to facilitate the lifting of the rack 3.

In Fig. 7 there is shown a T-shaped member 30, including a spring means for swinging the tray 10 outwardly, and including also the bottom 33 of the rack 3. This T-shaped member comprises a head 31, and a tongue 32 outstand from one end of the head 31, at right angles to the head. The head 31 is secured to the lower end of the rack 3, so as to form the bottom 33 thereof, as shown most clearly in Figs. 3 and 4. The tongue 32 extends upwardly between the back 11 of the tray and the back 4 of the rack 3. If desired, that portion of the tongue which is denoted in Fig. 7 by the numeral 35, may be secured to the back 4 of the rack 3. Intermediate its ends, the tongue 32 is bent as shown at 31, so that the free end of the tongue, engaging the back 11 of the tray 10, will serve to swing the tray 10 outwardly, as shown most clearly in Fig. 4.

Obviously, the bottom 33 of the rack 3 serves to protect that end of the hypodermic syringe 24 which projects through the opening 18. Upon the back 4 may be placed clips 105 holding a double-ended case 106 adapted to hold hypodermic needles.

In practical operation, by removing the caps 26, either of the clinical thermometers 125 may be withdrawn, as clearly indicated in Fig. 2. When it is desired to have access to the hypodermic syringe 24 or to the bottles 22, the rack 3 is withdrawn from the case 1, through the instrumentality of the milled bottom 27. When the rack 3 has been elevated sufficiently, the spring tongue 32 will swing the tray 10 outwardly, into the position shown in Fig. 4, the upper ends of the bottles 22 passing from beneath the ledges 23, whereupon any of the bottles, or the hypodermic syringe 24 may be readily removed from between the pins 21, and from behind the spring tongues 16 or 17. When the rack 3 is thrust into the case 1, the forward edges of the walls 14 of the tray 10 will engage the upper, front edge of the case 1, swinging the tray 10 inwardly, and putting the spring tongue 22 under compression. The case 1 possesses sufficient resiliency so that when the rack 3 is slid into the case, the part 25 will snap into engagement with the projection 29 on the case. The parts 25 and 29 may be disengaged by rotating the button 27.

The device is preferably fashioned from metal throughout, so as to withstand hard usage, and so that it may be readily sterilized.

With the case herein disclosed, any commercial form of bottle may be used and there is no occasion for shifting the medicine from bottle to bottle. There is therefore, no chance of erroneously mixing the contents of the bottles. The case is so shaped that it fits the pocket, and does not move about therein. The case may be locked in a closed position with equal facility, whether full or empty. The bottles are so held that the labels upon them will not be marred or obscured.

Having thus described the invention, what is claimed is:

1. In a device of the class described, a case open at one end; a rack open at the front and slidably inserted into the case; a tray pivotally connected with the rack, adjacent the inner ends of the tray and the rack; and adapted to swing outwardly through the open front of the rack; the tray having an article-supporting bottom provided with article-holding tongues, there being an article-receiving opening in the bottom, aligned with one tongue.

2. In a device of the class described, a case open at the top; a rack open at the front and slidably within the case; a tray pivotally

connected with the rack, adjacent the inner ends of the tray and the rack; spring means for swinging the tray outwardly, through the open front of the rack; and means upon the tray for holding an article upon the tray when the tray is actuated by the spring means.

3. In a device of the class described, a case open at the top; a rack open at the front and slidable within the case; a tray pivotally connected with the rack, adjacent the inner ends of the tray and the rack; article-holding means upon the tray; spring means for swinging the tray outwardly, through the open front of the rack; inter-engaging elements upon the rack and the case, to prevent a complete withdrawal of the rack from the case; and a locking device upon the rack, adapted to engage the case to maintain the rack within the case.

4. In a device of the class described, a case; a rack slidably mounted in the case; a tray pivotally connected with the rack, adjacent the inner ends of the tray and the rack; the tray consisting of a back, side walls and a bottom, the bottom being equipped at its outer edge with a plurality of upstanding spring tongues, and the back being corrugated to form article-receiving seats, alined with the tongues.

5. In a device of the class described, a case; a rack slidably inserted into the case; and a tray pivotally connected with the rack, adjacent the inner ends of the tray and the rack; the tray consisting of a back and an outstanding bottom the bottom being equipped at its outer edge with an upstanding, article-engaging tongue, there being a depressed, article-receiving seat in the back, alined with the tongue and an opening in

the bottom alined with the tongue and adapted to receive the point of the article; the rack having a bottom, adapted to protect the point of the article, the bottom being formed with an upstanding spring tongue, ⁴⁵ adapted to bear against the tray, to swing the tray away from the rack.

6. In a device of the class described, a case; a rack slidably mounted within the case and provided along its edges with ⁵⁰ tubular compartments, constituting reinforcements for the rack; a tray located between the tubular compartments; pivot elements mounted in the tubular compartments, and engaging the tray adjacent its inner ⁵⁵ end; and a spring plate secured to the rack and engaging the tray, to swing the tray, at its free end, away from the rack.

7. In a device of the class described, a case; a rack slidably inserted into the case ⁶⁰ and open at its front; a tray pivotally connected with the rack, adjacent the lower ends of the tray and the rack, the tray being provided at its lower edge with article-holding tongues, the back of the tray being ⁶⁵ corrugated, to form article-holding means alined with the tongues; projections outstanding from the back of the tray, to separate the articles; and a ledge outstanding from the rack and coöperating with the ⁷⁰ tongues to hold the articles against longitudinal movement.

In testimony that I claim the foregoing as my own, I have hereto affixed my signature in the presence of two witnesses.

FRANCIS W. BRIGGS.
